UNITED STATES PATENT OFFICE.

JOHN SODERBERG, OF CHICAGO HEIGHTS, ILLINOIS.

DEVICE FOR CASTING ELBOWS FOR STOVEPIPES.

1,117,269.

Specification of Letters Patent. Patented Nov. 17, 1914.

Application filed March 15, 1913. Serial No. 754,474.

To all whom it may concern:

Be it known that I, JOHN SODERBERG, a citizen of the United States, residing at Chicago Heights, in the county of Cook and 5 State of Illinois, have invented certain new and useful Improvements in Devices for Casting Elbows for Stovepipes.

The object of my invention is to provide means to cheapen the production of cast 10 iron elbows for stove pipes and render it possible to sell the same at the same or at a less cost than can corrugated stove pipe elbows be sold.

The manner in which I accomplish my object is set forth in the following specification and illustrated in the accompanying drawings, in which—

Figure 1 is a plan of that part of a green sand mold which is known as the "drag," 20 with a green sand core set in position therein, with broken lines indicating a separable core rod within said core. Fig. 2 is a plan (inverted), of the other part of a mold, known as the "cope." Fig. 3 is a vertical 25 section, on line 3—3 of Fig. 1, viewed in the direction indicated by the arrows. Fig. 4 is a plan of the pattern used in making the mold of the device. Fig. 5 is a side elevation of said pattern. Figs. 6 and 7 are plan 30 and side elevation, respectively, of the bottom of the core box used. Figs. 8 and 9 are plan and elevation, respectively, of the top of the core box. The dotted lines in Figs. 7 and 9, respectively, indicate a vertical section midway of and parallel to the top and bottom lines of said figures. Figs. 10 and 35 11 are plan and elevation, respectively, of the two-part core rod of the device. And Figs. 12 and 13 are plan and elevation of 40 four cast elbows, gate and core rod, freed from the sand of the mold.

A reference character applied to designate a given part indicates said part throughout the several figures wherever the same appears.

14 indicates the bottom board, the side members of the mold flask and the cleats on the bottom board.

15 indicates green sand which is used to 50 form the drag or bottom half of the mold illustrated in Figs. 1 and 3. The impression in the drag and cope is made by a pattern which is shown in Figs. 4 and 5. This pattern is adapted for the casting of four 55 elbows, separated in the middle by the core

prints 18. In the center of this pattern is the gate, 19, and core rod prints 20. The core 21 is formed in a core box consisting of two members, a bottom 22 and top 23, (Figs. 6, 7, 8 and 9). In the bottom of the 60 core box are two transverse channels, 24. Supported in these channels, or at least properly positioned thereby, are the arms 25 of the core rod 31. Core rod 31 consists of the members 26 and 27. The ends of one 65 of the members 26, 27 fit into the ends of the other of said members, and said members are joined together when said ends are so fitted and are firmly secured in said joined condition by the screw 28. When the two 70 members 26 and 27 of the core rod 31 are joined together, as shown in Figs. 10 and 11, and said core box has the bottom member 22 partially filled with sand, said core rod is placed on said sand and some additional 75 sand placed thereover. The top of the core box (23) is then put in place and the core is rammed up through the holes 29. The bottom of the drag is filled with sand, with the pattern in place therein. On the removal 80 of the pattern from the sand in the drag and cope the core is put in place in the mold in the drag, supported by the core prints 18. Suitable tools may be attached to the core by means of arms 25, in setting it into the 85 mold as above described. The metal is then poured. When the casting is removed from the flask the gate, (19) is broken away from the four elbows; the core sand broken away from the screws 28, the screws released, and 90 the members of the core rod, (26 and 27) are separated from each other; after which they are withdrawn from the elbows. Thus, by the use of a green sand core containing a two part core rod, said parts arranged to be 95 separated when desired and to be firmly secured together when necessary, and a green sand mold, and the casting of four elbows on one gate, I make the casting of said elbows a cheap and desirable operation, producing 100 cast iron elbows as substitutes for sheet metal elbows for stove pipes.

I claim:

To cast stove pipe elbows, a pattern consisting of a plurality of elbows, core prints 105 connecting said elbows, additional core prints, a centrally positioned gate, and radially extending runners connecting said gate and said elbows, in combination with a core comprising a core rod consisting of 110

separable parts and green sand, said core rod provided with abutments extending outside of said green sand and adapted to form means to handle said core, the green sand of 5 said core which corresponds to the core prints connecting said elbows being duplicates of said core prints, and said projecting

abutments being substantial duplicates of said additional core prints.

JOHN SODERBERG.

In the presence of—

CHARLES TURNER BROWN,

JULIUS RUBINSTEIN.
